(57) **CLAIM**

The ornamental design for a battery housing, as shown and described.

DESCRIPTION

FIG. 1 is a side perspective view of a battery housing showing my new design;

FIG. 2 is a first side view thereof;

FIG. 3 is a second view thereof;

FIG. 4 is a top view thereof;

FIG. 5 is a bottom view thereof;

FIG. 6 is a rear view thereof; and,

FIG. 7 is a front view thereof.

The broken line showing of a region in FIG. 6 and the unshaded area therein forms no part of the claimed design.
